UNITED STATES PATENT OFFICE.

HARVEY E. KAILER, OF CHICAGO, ILLINOIS.

MEANS FOR PREVENTING THE FREEZING OF THE COOLING SYSTEMS OF AUTOMOBILES.

1,144,939.

Specification of Letters Patent. Patented June 29, 1915.

Application filed March 28, 1914. Serial No. 827,828.

To all whom it may concern:

Be it known that I, HARVEY E. KAILER, a citizen of the United States, and resident of Chicago, in the county of Cook and State 5 of Illinois, have invented certain new and useful Improvements in Means for Preventing the Freezing of the Cooling Systems of Automobiles, of which the following is a full, clear, and exact specification.

10 This invention relates to improvements in means for preventing the freezing of the cooling systems of automobiles exposed to a water freezing temperature when at a standstill, and for which purpose the com- 15 mon and general practice prior to my invention has been to keep the engine running, or else introduce into the system a necessarily small quantity of alcohol, and to in extremely cold weather simultaneously em- 20 ploy both of these means.

The running of the engine of an automobile at a standstill is not only objectionable because of the expense incurred for fuel, to say nothing of the wear and tear produced, 25 but because of the liability of its accidentally running away, if not from being stolen, whereas on the other hand the use of alcohol is objectionable not only because of its cost, but for the reason that it can 30 only be used in a comparatively small amount, and at best evaporates so quickly that its efficiency cannot be relied on when most needed.

The object of my invention broadly stated 35 is to prevent for an indefinite time and at a minimum cost of construction and operation the water cooling system for an engine from freezing when exposed to extreme cold weather by means of a comparatively small 40 stream of heated water, hot enough to induce and maintain continuous circulation therein, and so small that it will not raise the temperature of the cooling water materially or substantially above the degree it 45 must have for cooling the engine, and at the same time make it possible and practical to utilize the cooling system water for that purpose.

A further object of my invention is to so 50 divert water from the cooling system of an engine for the purposes above described, that its current shall be generally in the same direction as that of the cooling water, and whereby the diverted water may not 55 obstruct the free circulation of the cooling water at any point of the cooling system.

A still further object of my invention is a means by which it is possible and practical to apply heat to and heat to quite a high degree a small fractional part of the body 60 of the diverted water whereby the smallest possible stream of water may be injected into the cooling system at the required degree of heat for maintaining continuous circulation throughout the cooling system, and 65 at a corresponding reduction in the volume and the expense of its production.

With these ends in view, my invention finds embodiment in certain features of novelty in the construction, combination and 70 arrangement of parts by which the said objects and certain other objects are herein-after attained, all as fully described with reference to the accompanying drawings, and more particularly pointed out in the 75 claims.

In said drawing: Figure 1 illustrates in front elevation the water cooling system of an automobile, and anti-freezing device therefor, connected in its operative position therewith, and in which my invention finds embodiment. Fig. 2 is a detail side elevation of the radiator of an automobile showing the device of my invention in its operative position relative thereto. Fig. 3 85 is an enlarged detail vertical section on the line 3—3 of Fig. 2 looking in the direction indicated by the arrows. Fig. 4 is a transverse section on the line 4—4 of Fig. 3. Fig. 5 is an enlarged detail vertical section 90 through the valve and huddling chamber of my device, and Fig. 6 is a horizontal section taken on the line 6—6 of Fig. 5 looking in the direction of the arrows.

Similar characters of reference indicate 95 the same parts in the several figures of the drawing.

The radiator 7 shown in Figs. 1 and 2 is a construction commonly employed and through which a circulation of cooling water from a suitable source is conducted through the pipe 8 at the bottom of the radiator, and discharged through the pipe 9 at the top thereof, the radiator as usual being provided with a removable plug or 100 cap 10.

In carrying out my invention the pipe 8 by means of a pipe 11 is connected with and opens into an auxiliary water chamber 12, the outlet for which is a pipe 13 screw-threaded for a substantial portion of its length as indicated at 14, with its upper

end projecting upwardly into an expansion chamber 15, from which the water discharges through an opening 16 below the open end of the pipe 14 connected with the 5 upper part of the radiator below the discharge pipe therefor, by a nipple 17, a small perforation 18 in the top of the expansion chamber immediately above the pipe 14 serving as a means for the escape of steam 10 and air accumulating therein, and thereby preventing an undue pressure in the pipes 14 and 17. To the lower end of the pipe 14 is secured in any suitable manner to form a tight joint with the pipe an inverted cup-like device 19, the bottom of which consists of a ring 20 removably screwed thereon for supporting a concavo convex plate 21 by means of radial arms 22.

The concavo convex plate 21 is the sole 20 and axial support for a disk valve 23 of less diameter than the internal dimensions of the cup device 19, whereby there may be at all times a free circulation of water upwardly between the radial arms 22 and around the 25 disk valve 23, and therefore through the pipe 14, the upward movement of the disk valve being limited by an annular shoulder 24 internally of the part 19. Concavo convex plate 21 may be suspended slightly 30 above the walls of the semi-spherical chamber 25, but in practice is closely fitted to or rests upon the chamber 25, which for convenience is here designated as a "huddling chamber." The disk valve 25, plate 21 and 35 huddling chamber 25 are respectively provided axially with perforations 27, 28 and 29 through which a supply of water may enter the chamber 25, and which on being heated discharges through these several devices into the pipe 14, and whereby means 40 are provided for raising to a very high degree of heat a very small portion and fractional part of the water in the reservoir 12, and discharging a fine stream of hot water 45 directly into the circulating system for the radiator, producing a circulation therein without substantially raising the temperature of the main body of the circulating water.

50 It will now be observed that the reservoir 12 will, in the operation of the device contain a volume of water, the gravity of which is sufficient to prevent the escape of steam from around the edges of the smaller reservoir 55 formed by the cup device 19, and otherwise producing more or less of a back pressure in the supply pipe 11, while at the same time the heat from the smaller reservoir and the pipe 14 is utilized for initially heating 60 the water in the auxiliary reservoir. Directly below the bottom of reservoir 12 is a vapor burner for supplying heat thereto inclosed within a shell or flange 30 depending from and preferably cast with the bottom 65 of the water chamber and provided at its

outwardly exposed side with a hinged door 31 for access to the burner.

The vapor burner above referred to consists essentially of a box-like structure 32 provided with a removable cap or cover 33 having therethrough a series of perforations 34 and secured to the sides of the shell 30 by means of nuts 35 and bolts 36, the bottom end of which shell is open. Projecting through and adjustable in the cap 33 is a 75 needle valve 37 opposed by a perforation 38 surrounded by the seat for the valve by means of which perforation gasoline from the engine may be supplied through the pipe 39 to the burner. Surrounding the seat for 80 the needle valve is an inverted cone deflector 40, the walls of which and of the point of the needle valve 37 are approximately parallel, that is to say so inclined that gasoline discharging from the passage 38 will be deflected by the cone shaped point of the needle valve outwardly therefrom and by this means be supplied throughout the combustion chamber and correspondingly more uniformly intermingle the air admitted to this 90 chamber through small perforations 41 through the mixing chamber, and thereby secure a proper mixture of oil and gas projected through the perforations in the cap, and there ignited for applying heat to the 95 water in the water chamber 12, the proportions of oil to a given amount of air being regulated by the needle valve, the head 42 of which is accessible through the door 32 for that purpose. To prevent the accumulation of oil in the mixing chamber or such a quantity as might possibly produce an explosion, the inverted cone 40 is provided with a perforation 43 extended through the bottom of the mixing chamber through 105 which such oil may be discharged.

It will now be observed that the huddling chamber 25 being on a line axial with the burner, and surrounded as it were by the perforations 34 in the cap 33 is thereby 110 located at a point directly over and where there is the greatest concentration of heat from the burner, and that being in communication with the water in the reservoir, it serves to so huddle a portion of the water 115 therein that it is possible and practical to thereby heat a comparatively small body of water to a very high degree of heat, and discharge it upwardly directly into and through the pipe 14 and thence onwardly 120 into the water cooling system of an automobile in the path of the current of the cooling water circulating therethrough, while in the meantime the temperature of the water in the reservoir surrounding the pipe 125 14 is maintainable at a much lower temperature but sufficiently warm to prevent the substantial chilling of the hot water, and steam perhaps therethrough in the pipe 14.

It is not the intention or purpose of my 130

invention to apply heat to or substantially raise the temperature of the cooling water in the circulating system, but to project therein and in the direction of its current a very small stream of water, the degree of heat of which will maintain a circulation of water throughout the system, and the temperature of moving water below its freezing point.

10 It is for the purpose of avoiding the possibility of raising the temperature of the circulating water substantially above its freezing point that the disk valve 23 is employed, the operation of which is, that when 15 the temperature of the water in the bottom of the reservoir and adjacent the disk valve is high enough to heat the water in the circulating system if permitted to discharge therein water so heated, will exert a force 20 lifting the valve to its seat against the shoulder 24 and thereby limit the passage of hot water therethrough to the axial perforation of the valve, which being quite small restricts the cooling water to the reception of 25 but a very fine stream of heated water, which, however high the degree of heat applied thereto cannot raise the temperature of the cooling water to a degree substantially reducing its effectiveness, as a cooling medium for the engine.

In short it is made possible and practical by my invention to promote the circulation of water in a cooling system for automobiles in a non-freezing temperature, and to prevent 35 the water from freezing therein when the engine is at a standstill, and no longer supplies heat thereto in the coldest of weather for an unlimited time, and at a minimum cost of operation of the device accomplishing this most important object.

In conclusion it should be observed that the device by which water is diverted from the cooling system and returned thereto in a heated condition constitutes a branch in the 45 water cooling system, and that my invention is not limited to its location as herein shown and described, if and when located and connected to some other point therein substantially the same results will be produced.

50 Having described my invention, what I claim and desire to secure by Letters Patent is:

1. The combination with a water cooling system for engines, comprising a radiator, a 55 water jacket and an inlet and outlet pipe for the radiator, of means diverting water from and returning it into the current thereof, means for isolating a small portion of water from, and returning it in the form of a jet 60 into the diverted current, and means for heating said isolated water, whereby a continuous circulation of water in a cooling system exposed to a freezing temperature is maintained without substantially reducing 65 the cooling efficiency of the water therein.

2. The combination with a water cooling system for engines comprising a radiator and a water jacket, and an inlet and outlet pipe for the radiator, of means diverting the water from and returning it into the current thereof, means for contracting the diverted current of water, and means for applying heat to the contracted portion of said water current.

3. The combination with a water cooling system of an engine, comprising a radiator, a water jacket, and a supply and discharge pipe therefor, of a pipe externally of the radiator connecting said inlet and outlet pipe provided with an intermediate contracted passage for the water, a valve for controlling the passage of water therethrough, and means for applying heat to the contracted current of water during its passage from the inlet to the outlet pipe of the 85 radiator.

4. The combination with the water cooling system for an engine, of means for diverting a small stream of water therefrom and returning it into the current thereof, an 90 enlarged water chamber therein, means for isolating a small portion of the water in said chamber, and means for isolating and applying heat to a fractional part thereof, and directing it in a heated condition onward to 95 the cooling water.

5. The combination with the water cooling system for an engine comprising a radiator and water jacket, of a water heating branch therefor, comprising an outlet pipe 100 and an inlet pipe in open communication with the cooling water of said system, a water reservoir connecting said pipes and in the path of the current of water therethrough, means for applying heat to the contents of said reservoir, and a water huddling chamber therein directly in the path of the current of water flowing through the inlet pipe to the cooling system, whereby a comparatively very small amount of the water in the reservoir may be highly heated and discharged into the cooling system in a small stream for maintaining continuous circulation therein without substantially increasing the temperature of the cooling 115 water.

6. A water cooling system for engines comprising a radiator and a water jacket, a water heating system branching therefrom, an outlet pipe therefor, a water reservoir 120 into which said pipe projects, means suspended from said pipe forming a water chamber open at its bottom end, a disk valve therein, provided with a central perforation, a seat for said valve, and a stop therefor for 125 limiting the volume of water passing from the reservoir to the said outlet pipe.

7. A water cooling system for engines comprising a radiator and a water jacket, provided with a branch system for heating 130

water diverted therefrom, comprising in combination a water reservoir, an inlet pipe therefor, a discharge pipe projecting therein and terminating above the bottom thereof, a contracted water chamber suspended therefrom, a disk valve therein, a seat therefor, a water huddling chamber below said seat, an open passage through said valve, seat and huddling chamber in the path of 10 the current of water through the discharge pipe, and a burner beneath the huddling chamber and the reservoir whereby the contents of the huddling chamber is heated to a

substantially higher degree than the body of water in the reservoir and passes thence in 15 a direct line to the discharge pipe and the flow of the water from the reservoir to said pipe is adjustably restricted.

In witness whereof, I have hereunto set my hand and affixed my seal, this 26th day of 20 March, A. D. 1914.

HARVEY E. KAILER. [L.S.]
